MUSICAL INSTRUMENT TOY

John W. Ryan, Bel-Air, and John H. Goetz, Sherman Oaks, Calif., assignors to Mattel, Inc., a corporation of California

Filed Nov. 4, 1965, Ser. No. 88,000

Term of patent 14 years

(Cl. D56—1)

We claim:

The ornamental design for a musical instrument toy, as shown.
